UNITED STATES PATENT OFFICE.

MICHAEL KUNIK, OF CHICAGO, ILLINOIS.

FENDER FOR SHIPS.

1,156,086.

Specification of Letters Patent.

Patented Oct. 12, 1915.

Application filed December 2, 1914. Serial No. 875,090.

To all whom it may concern:

Be it known that I, MICHAEL KUNIK, a subject of the Emperor of Austria-Hungary, residing at Chicago, in the county of Cook 5 and State of Illinois, have invented new and useful Improvements in Fenders for Ships, of which the following is a specification.

This invention relates to safety devices for 10 water craft, and particularly to the class of fenders for ships, boats and the like.

An object of the invention is the provision of a fender that will eliminate or lessen the destruction to a ship or boat or the like, 15 due to collision with another vessel, or any other object.

To this end and purpose my invention consists in the novel construction, combination and arrangement of parts herein described, shown in the accompanying drawings, and more particularly brought out in the claims.

In the illustrations Figure 1 is a plan view of my invention as applied to a bow of a 25 ship and Fig. 2 a side elevation of same.

Like reference characters indicate like or corresponding parts.

Referring to the drawings, I provide a plurality of compressed air cylinders 1^a, 1^b, 30 1^c and 1^d arranged in pairs symmetrically about the center line "X—X" of the vessel.

Each cylinder end is provided with neck 1^e and solid ball 1^f supported and arranged to operate within the member 2 as in a ball 35 and socket joint. The member 2 is securely riveted to the ship's hull B.

Each cylinder is provided with a piston 1^g and piston rod 1^h at the end of which are perpendicularly disposed rams 4 pivotally 40 mounted at 4^a and held normally with the sharp end forward by means of the spring 5, bars 6 and arms 7 secured at 4^c.

Attached, preferably above the water line, 45 is a plurality of members or feelers 8 with rollers 8^a and 8^b, arranged to engage the approaching object and thereby rotate the vertical rams 4 so that the flat side 4^b engages said object.

Each pair of piston rods 1^h is pivotally 50 connected at 9^a with a horizontal ram 9, and each pair of cylinders is held in a fixed, spaced relation by means of a connecting rod 3, pivotally mounted at 3^a and arranged for horizontal movement through the loose washers 3^b and horizontally elongated openings 10 in the bow of the ship. A pair of 55

heavy coil springs 3^c arranged between the washers 3^b and fixed collars 3^d, tend to retain each of cylinders in parallel alinement with the center line "X—X" of the ship 60 and also act as shock absorbers in case of side collision, as shown dotted in Fig. 1.

The ball and socket joint mentioned permits side movement of the cylinders within the angle "A" and in such movement compresses one of the coil springs 3^c.

For purposes of charging the cylinders with air and testing same at frequent intervals I provide a one-way exhaust valve 12 through which the air escapes as the piston 70 moves forward to position shown on drawings.

Air is supplied from a pump or other means through pipe 13 in the air chamber 14 which is equipped with a pressure gage 75 15. The valves 16^a, 16^b, 16^c and 16^d successively and alternately admit the air into their respective cylinders through the pipes 17^a, 17^b, 17^c and 17^d. A flexible pipe 18 is provided to accommodate the movement of 80 cylinders within angle "A".

When a cylinder is filled with compressed air to the required pressure indicated at the gage 15 the valve 19 is first closed and then the respective valve 16^a, 16^b, 16^c or 16^d. 85

In a straight line collision with an object engaging the ram 9 or feelers 8 and vertical rams 4 all of said pistons 1^g would compress the air within the cylinders which would act as a cushion and absorb the shock, while in any side collision which would tend to move the cylinders in the angle "A" both cylinders and the coil spring 3^c may absorb the shock or the coil spring 3^c alone, depending on the angle in which the collision 90 occurred.

It is thought that the foregoing description of construction and operation will be clearly understood, therefore, a more extended explanation is omitted.

I claim as my invention:

1. The combination in a fender for ships, of a plurality of pivotally mounted air cylinders, rams, and means for supporting said cylinders.

2. The combination in a fender for ships, of a plurality of pivotally mounted air cylinders, horizontal and vertical rams and means for supporting said cylinders.

3. The combination in a fender for ships, of a plurality of pivotally mounted, pairs of air cylinders, horizontal and vertical rams

attached thereto and means for supporting said cylinders to permit horizontal movement.

4. The combination in a fender for ships, 5 of a plurality of pivotally mounted pairs of air cylinders, horizontal and vertical rams and resilient means for retaining said cylinders in parallel alinement with the center line of the ship and means for supporting 10 said cylinders arranged to permit horizontal movement of same.

5. The combination in a fender for ships, of a plurality of air cylinders connected

vertically and horizontally with rams, means for supporting said cylinders arranged to 15 permit horizontal angular movement of said cylinders and resilient means arranged to retain said cylinders in parallel alinement with the longitudinal center line of the ship.

In testimony whereof I affix my signature 20 in presence of two witnesses.

MICHAEL KUNIK.

Witnesses:

LOUISE HENNESSY,
JOHN BELL.
